UNITED STATES PATENT OFFICE

AUGUSTINE SHELBYNE, OF SOUTH PASADENA, CALIFORNIA

AIR-BRUSH NOZZLE

Application filed January 27, 1927. Serial No. 163,903.

My invention is an air brush nozzle of the type for blowing paint or like material by means of compressed air, and having an air nozzle rotatable in relation to the fluid nozzle, whereby a straight or spread jet of fluid may be had by injecting the air at a lateral inclination on a central fluid jet.

My invention pertains particularly to the nozzle construction of an air brush of the type in which a central fluid jet has an annular air jet surrounding same and ejecting the fluid and also a pair of lateral air jets diametrically opposite which impinge on the central liquid jet. In this type of nozzle it has been difficult to have the central fluid jet properly centered so that the annular air jet surrounding same is equal on all sides, also it is difficult to have the liquid jet projected in the proper relation to the lateral jets so that these will impinge on same at diametrically opposite points and cause the proper spreading of the liquid.

A main object of my invention is to construct the nozzle with the control device for the jets mounted in a floating manner in relation to the rotatable lateral air jets. This causes the device to have a self-centering action so that the annular air jet and the liquid jet are in proper centered relation. The construction facilitates action of the lateral air jets.

In constructing my invention I use substantially a known type of air brush having a suitable trigger control or the like for a valve controlling the flow of liquid, the air brush stock has a bore in its outer end and a liquid tube is inserted in this bore, being connected to a liquid receptacle. The space surrounding the liquid tube in the bore forms an air chamber, having connection with a source of air under pressure. The fluid tube has a flange on its outer end which extends slightly beyond the circumference of the stock of the brush, there preferably being a packing member between the flange and the end of the stock. The tube terminates in a tapered discharge nozzle.

The lateral rotatable air nozzle is connected to the flange of the liquid tube by means of a coupling nut which engages said

flange on the side adjacent the stock and allows tight or loose adjustment of the lateral air nozzle in reference to the liquid tube and its discharge nozzle. The air jet nozzle has a pair of passages located diametrically opposite and the front of the flange of the liquid tube is provided with a plurality of passages which are substantially tangent to the base of the cone forming the discharge nozzle. There are a plurality of ducts through the flange from these passages to the air chamber. By this construction there are provided a plurality of passages connecting to a plurality of ducts leading from the air chamber giving sufficient air to supply the annular jet as well as the lateral jets.

My invention will be more readily understood from the following description and drawings, in which:

Figure 1 is a longitudinal sectional view of discharge end of an air brush.

Figure 2 is a side elevation of the liquid tube with its discharge nozzle and the flange constructed integral with such tube.

Figure 3 is a front elevation of the discharge tube, taken in the direction of the arrow 3 of Fig. 2.

Figure 4 is a transverse section through the nozzle on the line 4—4 of Fig. 1 in the direction of the arrows.

Figure 5 is an end elevation of the nozzle taken in the direction of the arrow 5 of Fig. 1.

In the drawings the stock of the air brush is designated by the numeral 1 and has an enlarged bore 2 at the discharge end. There is a reduced threaded section 3 at the base of the bore leading into the liquid chamber 4 to which a liquid passage 5 connects, this passage being connected in any suitable manner to a liquid receptacle. An air passage 6 extends through the upper part of the stock, there being an air opening 7 into the bore 2.

The air passage is closed by a plug 8 at its front end. The end 9 of the bore is preferably cylindrical. The air is supplied to the brush in any suitable manner and may be in accordance with the construction set forth in my Patent 1,586,010 issued May 25, 1926.

The construction of the liquid tube is substantially as follows:

55

This tube is designated generally by the numeral 10, being shown in detail in Figs. 2 and 3. It comprises a tubular body structure 11, having a screw threaded end 12 to fit in the screw threads 3. A base flange 13 has a washer 14 bearing on the seat 15 at the base of the bore 2. An outer flange 16 has a shoulder 17 on which is mounted a washer 18, this washer fitting against the end 19 of the stock. 5 The nozzle 20 is cone shaped terminating in a slight cylindrical portion 21 to fit in the air nozzle, as hereunder set forth. A plurality of grooves 22 form air passages, being connected by ducts 23 from the back of the flange 10 to the front of the flange. These ducts thus connect with the chamber formed in the bore back of the flange 16. This may be designated the air chamber 24. It will be noted that I illustrate four main air passages which are 15 tangential to the base of the cone forming the liquid nozzle 20. These passages intersect and form a large air space 25 adjacent the perforated flange, separated by solid sections 20 26.

25 The air nozzle is constructed substantially as follows; having reference to Figs. 1, 4 and 5:

This nozzle is designated generally by the numeral 27 and has a circular base 28, which 30 is connected by an internally screw threaded coupling nut 29 to the flange 16, this coupling nut having an internally turned rim 30 engaging the outer periphery of the flange 16 on the shoulder 17, such shoulder projecting 35 preferably beyond the circumferential part 9 of the stock. The air nozzle has an internal cone section 31, thus forming an air jet chamber 32 for the annular air jet nozzle 33, which surrounds the liquid nozzle 34. A pair of opposite air passages 35 extend longitudinally 40 of the air nozzle and have inwardly directed air discharge jets 36.

The flow of liquid is controlled by a tapered valve member 37 which is connected to 45 a valve plug 38 of the usual construction, this having a stem 39 extending rearwardly through the liquid tube across the liquid chamber 4 and out of the rear end of the stock, there being a suitable packing 40 forming a liquid tight seal.

The manner of using and functioning of my nozzle for air brushes is substantially as follows:

It will be understood that the flow of liquid, 50 such as paint, through the air tube may be controlled in the usual manner by the valve 37 by manipulating the stem 39 and also by the pressure forcing the liquid to the nozzle. The coupling nut 29 may be clamped tight so 55 that the base portion of the air nozzle is pressed tightly against the outer surface of the flange 16 thereby bearing on the solid sections 26. When the air nozzle is in a position 60 so that the air passages 35 are in registry with the solid sections 26 of the flange 16, no air

can pass through such passages and the lateral air jets 36 are inoperative. The air forced in under pressure to the air chamber 24, however, may pass through the air ducts 23 and discharge in the form of an annular air jet 70 33, surrounding the liquid jet. When, however, the air nozzle is partly rotated so that the air passages 35 are in registry with the air space 25 at the end of the grooves or air passages 22, the air in addition is discharged 75 through the lateral air jets 36.

The coupling nut 29 rotates with the air nozzle when same is rotated and, if desired, this coupling nut may be connected somewhat loosely to the air nozzle so that it does not bear tightly on the shoulder 17 of the flange 16, in which case a certain amount of play in a front-and-rear direction and also a certain lateral wobbling motion is allowed the air nozzle in reference to the liquid tube and the liquid nozzle, therefore, when the nozzle is subject to air pressure in painting operations, the air nozzle has a self-centering function in relation to the liquid nozzle thereby maintaining the annular jet surrounding the liquid nozzle a true annulus and having the liquid nozzle properly centered therein. When the central air jet is properly centered surrounding the liquid jet, the lateral air jets 36 are also properly centered so that the air discharged therefrom impinges in the proper manner on the central liquid jet, thus giving an improved flow for the liquid, such as paint, when being sprayed. It is readily understood that the air nozzle may be rotated on the liquid nozzle when the coupling nut is slightly loose, just the same as when same is fitted tight.

In the above description it will be seen that I have constructed an air brush nozzle which 105 allows proper centering of the liquid and air jet by a type of floating action between the structure forming such jets and that I also provide passages for a large flow of air for both the liquid and the lateral air jets.

Having described my invention, what I claim is:

1. An air brush nozzle comprising in combination an air brush stock having a liquid nozzle connected thereto, an air nozzle, a nut having a threaded engagement with the air nozzle, inter-engaging means between the nut and the liquid nozzle, said means allowing slight movement of the nut and the air nozzle relative to the liquid nozzle.

2. An air brush nozzle comprising in combination an air brush stock, an integral liquid nozzle having a flange connected thereto, an air nozzle, a nut threaded on the air nozzle, inter-engaging means between the nut and the flange to allow the nut and the air nozzle to have a slight adjustment relative to the flange.

3. An air brush nozzle comprising in combination an air brush stock having a bore at

its outer end, an integral liquid nozzle having a tube, the tube being connected to the stock, forming a liquid tight connection, a flange on the outer end of the tube having air ducts, means forming an air-tight connection with the end of the stock, there being an air passage through the stock into the bore, an air nozzle having air ducts, a nut having threaded engagement with the air nozzle and inter-engaging means between the nut and the flange allowing slight movement of the nut and the air nozzle relative to the liquid nozzle.

4. An air brush nozzle comprising in combination a stock having a bore in the end, with an air passage connected to said bore, a liquid nozzle having a tube, the said tube being threaded into the base of the bore, there being a liquid passage in the stock connecting therewith, means forming a tight seal between the tube and the bore, a flange on the tube, a gasket forming a tight connection between the flange and the end of the stock, the flange having air passages and air ducts therethrough, an air nozzle having air ducts, a nut threaded on said air nozzle, a rim on said nut, said rim having an engagement with the said flange, and securing the air nozzle in adjustable relation to the liquid nozzle.

5. An air brush nozzle comprising in combination, an air brush stock having a bore at its outer end, a liquid nozzle having a tube inserted in the bore and having a flange, a closure means between the flange and the stock, a plurality of grooves on the face of the flange, air ducts through the flange from the bore to said grooves, and an air nozzle having a plurality of air passages and jets rotatably bearing upon said flange.

6. An air brush nozzle comprising in combination, an air brush stock having a bore at its outer end, a liquid tube fitted in said bore and having a flange, means forming a seal between the flange and the stock, the tube having an integral tapered liquid nozzle in the face side of the flange, the flange having a plurality of crossed grooves, air ducts through the flange to said grooves, and an air nozzle having a plurality of air passages and jets rotatably mounted against the face of the flange.

7. An air brush nozzle, as claimed in claim 6, said flange having solid sections adjacent its edge separated by air spaces, the air spaces being in registry with the air passages in the air nozzle in one position, the solid surfaces of the flange cutting off said air passages.

8. An air brush nozzle comprising in combination, a liquid nozzle construction having a flange, there being a stock with an air chamber back of the flange, the flange having a plurality of cross grooves forming air passages in its face, air ducts through the flange

to said passages, and an air nozzle having a plurality of air passages and air jets rotatably mounted on the face of the flange.

9. An air brush nozzle, as claimed in claim 8, the liquid nozzle construction and the air nozzle forming an air jet chamber with a discharge outlet surrounding the liquid nozzle, the grooves in the flange being crossed and forming air spaces adjacent the outer edge of the flange, separated by solid sections, the air nozzle in rotation being registerable with the air spaces or with the solid sections to project the jets or to shut off said jets.

10. In an air brush nozzle, a liquid nozzle having a flange with an integral tapered nozzle structure on the face of the flange, crossed grooves on the face of the flange to form air passages surrounding the tapered nozzle terminating in air spaces at the periphery separated by solid sections, there being air ducts from said grooves through the flange, an air nozzle having a plurality of passages and lateral air jets, there being an air jet passage and an annular air jet nozzle surrounding the liquid nozzle, and means rotatably mounting the air nozzle on the flange, whereby on rotation of the air nozzle the said passages may register with the air spaces on the flange or with solid sections adjacent the periphery of the flange.

11. An air brush nozzle comprising in combination, an air stock having a bore at its outer end, a tubular liquid nozzle having a flange with crossed grooves on its outer face, air ducts through the flange from the grooves, an air nozzle having a plurality of air passages connecting to lateral air jets, and a coupling nut screw threaded on the air nozzle and having a rim engaging the flange of the liquid nozzle.

12. An air brush nozzle comprising in combination an air brush stock having a tubular liquid nozzle connected thereto, said nozzle having a tapered outer end and an annular flange, a nozzle positioned to bear against said flange and forming an annular passage with the tapered extension of the said tube and having a pair of diametrically opposite air ducts, and a nut threaded on the air nozzle and having a flange inter-engaging with the flange of the said tube of the liquid nozzle, the said flange having a plurality of crossed grooves on its face with passages connecting through the flange to said grooves, the air nozzle at the said ducts being adapted to bear against the surface of the flange or to align with the said grooves.

In testimony whereof I have signed my name to this specification.

A. SHELBYNE.
